UNITED STATES PATENT OFFICE.

GEORGES CLAUDE, OF BOULOGNE-SUR-SEINE, FRANCE.

NEON-TUBE.

1,231,494.

Specification of Letters Patent. Patented June 26, 1917.

Application filed June 16, 1915. Serial No. 34,555.

To all whom it may concern:

Be it known that I, GEORGES CLAUDE, a citizen of the Republic of France, residing at Boulogne-sur-Seine, France, have invented certain new and useful Improvements in Neon-Tubes, of which the following is a specification.

The present invention relates to improvements in neon tubes for lighting purposes, and it aims primarily to overcome a defect which is inherent in neon tubes when employed for this purpose, and which frequently renders them incapable of use without their light being corrected in some way, owing to the excessive amount of red contained therein.

It has been proposed to effect such correction by means of light supplied by mercury tubes, which emit too little red light and too much green or violet light, but this has proven unsatisfactory for the reason that the ordinary mercury vapor tubes are worked by low-pressure continuous current, whereas neon tubes require high-pressure alternating current.

According to the present invention, the requisite correction is obtained by introducing a few drops of mercury into a neon tube and then passing an alternating current therethrough in the manner usual with neon tubes, the heat generated by the current soon volatilizing the mercury, the vapor of which fills the entire tube, while the neon radiations completely disappear. The radiations of the corrector tube, thus formed, are then added to the red radiations of an adjoining neon tube, giving a greatly improved resultant light. It is obvious, though, that in order to make the correction as perfect as possible, the red light of the neon tube, hereinafter termed the red tube, and the blue light of the neon and mercury tube, hereinafter termed the blue or corrector tube, must be suitably proportioned. It has been found that if the red tube and the blue corrector tube have the same diameter, and the same current is passed through both, the blue tube should be about twice as long as the red tube to obtain a good correction.

Figure 1 shows one embodiment of the invention;

Figs. 2, 3 and 4 show, each, a separate modification; and

Fig. 5 shows a diagram of the wiring used.

One arrangement which has proven satisfactory, consists in placing a straight neon tube A, (Fig. 1), between the two branches of a U-shaped tube B of the same diameter containing neon and mercury, and in passing the same current through both tubes; or in a generally similar manner, in interposing a neon tube between two blue tubes of practically the same length and of the same diameter, for instance an oval red tube A, (Fig. 2), between two blue ovals B and C, the whole being connected in series.

This arrangement has, however, the drawback of being too expensive, since it requires three adjoining tubes. Moreover, the color of the light supplied is generally not very satisfactory, approaching either mauve or a very pronounced pink. It would also be desirable to make this correction of a red tube by means of a single blue tube capable of following the same outline. The problem obviously consists in so disposing the tubes that the said single blue tube gives as much light as the two lengths of blue tube employed in the preceding arrangement. It can be easily solved if the red tube and the blue or corrector tube are supplied separately with different currents, as it will obviously be possible to choose the diameter of the corrector tube and the current passing through the same, in such a manner as to comply with the desired condition. The matter is more difficult when, the high voltage being produced by a transformer or by a Rumkorf coil, it is advisable to supply the two tubes in series with the same current, because in that case, the supply in parallel from a single transformer is a delicate matter.

An excellent solution of the problem is obtained by bearing in mind the following considerations:

Series of very complete measurements have shown that, with equal density of current, the fall of potential in the neon tubes, and in the neon and mercury tubes, is inversely proportional to the diameter, (*Comptes Rendus de l'Academie des Sciences*, 1 September, 1913, and 16 February, 1914), and that, even with equal currents, the smaller the diameter of the tubes, the greater the voltage required by them. Other measurements, (*Comptes Rendus*, 9 March, 1914), have shown that the quantity of light supplied by the tubes in question,

depends fairly exactly on the quantity of energy consumed by them. It follows from these investigations that if the same current is sent through two tubes of unequal diameter, it will be the smaller tube that will supply the greater quantity of light, as that tube will consume the greater quantity of energy, owing to the extra voltage that it requires. And it has, in fact, been found that a tube of unit diameter supplies, practically, twice as much light as a tube of twice the diameter through which the same current is passed. Thus, it is possible to replace the double length of blue corrector tube above referred to, by a single length B, (Figs. 3 and 4), of a tube of a smaller diameter connected in series with the red tube A to be corrected and preferably arranged very close to the latter.

This arrangement has numerous advantages. First, it is obviously the simplest method of rectifying the light by corrector tubes. This method is the best not only from the point of view of economy, as the corrector tube, being only of small diameter, is comparatively inexpensive, but also from the point of view of efficiency, as the constant loss at the electrodes is smaller relatively to the total voltage of the small tube.

It is also preferable from the point of view of safety, as the supply of the two tubes connected in series at one of their ends is effected through the other end, so that it is possible to do away with high-tension conductors, if desired. On the other hand, experience shows that with these blue tubes with great current density the light supplied is less pale and neutralizes the red of the neon in a more efficacious manner. Finally, the color of the light obtained can be varied with great exactitude merely by varying the diameter of the corrector tube. Thus if the diameter of the corrector tube is increased, the proportion of blue is reduced, while if the said diameter is reduced the proportion of blue is increased, and the light made more mauve.

All these advantages are therefore consequences of the arrangement herein claimed and consisting in the combination of a neon tube with a neon and mercury tube of practically the same length, the same current passing through both, but the latter tube producing a sufficient quantity of correcting light owing to its smaller diameter.

It is possible, for instance, to obtain easily portable lighting sets by the combination of two similar tubes of equal length, for instance 6 m., arranged almost side by side, the inside diameter of the neon tube, however, being 20 mm. while that of the neon and mercury tube is only 10 mm. These tubes may be straight, or either oval or circular in shape, as preferred, and in the last two instances are disposed concentrically.

In normal working, the two tubes constituting one of the sets above referred to, are, as already stated, mounted in series on the secondary winding of a transformer, a regulating self-induction coil being preferably inserted in the low pressure circuit. When lighting up, the neon in both tubes initially becomes luminescent, and it is only gradually that the blue or correcting light appears and develops, but the luminous intensity of the neon and mercury tube, when its light has become blue, is much less than that which it showed at first during the initial or red light stage. During the lighting up, therefore, there will be a very great luminous intensity in red which will quickly decrease as the blue progresses which will convey the disagreeable impression that the light is being gradually extinguished. Moreover, the corrector tube, when the neon is still predominant, requires a considerably higher voltage than afterward when the mercury dominates. It is, therefore, necessary to employ a fairly high-voltage transformer, in order to enable the lighting operation to progress without hesitation, and to give a stable working even during this initial period, such voltage being more than necessary for the normal working, which results in a very bad load factor, about 0.50.

The invention is completed in this respect by providing a means for avoiding this serious disadvantage. It consists in using a single transformer which is just sufficient for normal working, and in short-circuiting the red tube until the other tube emits blue light, by progressively varying the intensity or the voltage at the terminals, or by limiting the time of the said short-circuiting to a suitable period. Moreover, a suitable resistance or self-induction coil could be connected in series to the blue tube during the short-circuiting, for the purpose of avoiding an excessive current. In that way, sufficient voltage will be obtained for easily lighting up the blue tube, without producing an injurious excess of red light at the beginning, and as soon as the mercury appears, after a few seconds, the short-circuit is automatically cut out and the red tube becomes easily lighted in its turn, the voltage being now sufficient owing to the decrease of the difference of potential required by the blue tube.

This arrangement is moreover applicable to combinations of three tubes of the same diameter through which passes the same current, as mentioned in the foregoing.

A method of automatically obtaining this momentary short-circuiting of the red tube when lighting up, is, for instance as follows (Fig. 5):

When the switch inserted in the low-pressure circuit of the transformer is closed, the high-pressure current passes for a very short

time through the red tube A, the blue tube B, the electro-magnet E and the coil C; the armature F of the electro-magnet E is attracted, and the mercury contact G short-circuits the tube A. The coil C then heats and expands the core H which, after an interval during which the tube B becomes blue, engages the contact I, which short-circuits said magnet E. The plunger contact 10 G is then withdrawn from the mercury by the action of the spring R, and the tube A becomes operative.

I claim:

1. An electric lamp comprising two neon 15 tubes of suitable shape, grouped together

and mounted in series in the same high-tension circuit, one of said tubes containing a few drops of mercury.

2. An electric lamp comprising two neon tubes of the same length, mounted in series 20 in the same high-tension circuit, one of said tubes containing a few drops of mercury and having a diameter half that of the other tube.

In testimony whereof I affix my signature. 25

GEORGES CLAUDE.
